[57] CLAIM

The ornamental design for a table for use on an arm chair, as shown and described.

DESCRIPTION

FIG. 1 is a perspective view of the table for use on an arm chair embodying the design of the present invention;

FIG. 2 is a front elevational view thereof;

FIG. 3 is a rear elevational view thereof;

FIG. 4 is a side elevational view thereof;

FIG. 5 is a side elevational view thereof; and,

FIG. 6 is an end elevational view thereof, the end opposite being a mirror image of the end shown in FIG. 6.

FIG. 1.

FIG. 2

FIG. 3.

FIG. 4.

FIG. 5

FIG. 6.
